HEATING ELEMENT TIP FOR SKI REPAIR

Alvis R. Knowles, Torrance, Calif., assignor to Eldon Industries, Inc., Hawthorne, Calif., a corporation of California

Filed Nov. 15, 1967, Ser. No. 9,425

Term of patent 14 years

Int. Cl. D8—02

U.S. Cl. D26—1

FIG. 1.

FIG. 7

FIG. 2.

FIG. 3.

FIG. 4.

FIG. 5.

FIG. 6.

FIG. 1 is an isometric view of a heating element tip for ski repair embodying my new design;

FIG. 2 is a side elevational view of one side of this tip;

FIG. 3 is a front end elevational view of this tip;

FIG. 4 is a top plan view of this tip;

FIG. 5 is a rear end elevational view of this tip;

FIG. 6 is a bottom plan view of this tip; and

FIG. 7 is a partial longitudinal cross sectional view of the tip shown, illustrating the interior construction at the rear end of this tip.

The side of the tip embodying my new design not illustrated has the appearance of a mirror image of the side of this tip illustrated in FIG. 1.

I claim:

The ornamental design for a heating element tip for ski repair, substantially as shown and described.
